UNITED STATES PATENT OFFICE.

WILLIAM H. BROTHERS, OF CLEVELAND, OHIO, ASSIGNOR TO THE COLUMBIAN HARDWARE COMPANY, OF CLEVELAND, OHIO, A CORPORATION OF OHIO.

DESIGN FOR A SCREEN-DOOR HINGE.

No. 38,992.

Specification for Design.

Patented Jan. 7, 1908.

Application filed October 5, 1906. Serial No. 337,642. Term of patent 3½ years.

To all whom it may concern:

Be it known that I, WILLIAM H. BROTHERS, a citizen of the United States, residing at Cleveland, in the county of Cuyahoga and State of Ohio, have invented a new, original, and ornamental Design for Screen-Door Hinges, of which the following is a specification, reference being had to the accompanying drawing, forming a part thereof.

Figure 1 is a perspective view of a screen door hinge showing my new design. Fig. 2 is an end elevation thereof.

What I claim is:

The ornamental design for a screen door hinge, as shown.

Signed at Cleveland this 25th day of Sept. 1906.

WILLIAM H. BROTHERS.
